PAUL THEODORE BEYGRAU, OF BERKELEY, CALIFORNIA.

WALL BOARD.

Application filed November 17, 1925. Serial No. 69,691.

The present invention relates to new and useful improvements in wall board and it pertains more particularly to a composition board for use in facing walls in buildings.

- 5 It is one of the primary objects of the invention to provide a wall board which may be used in the erection of walls, which board will give to the completed wall a finished appearance.
- 10 It is a further object of the invention to construct the wall board in such a manner that when a plurality of the boards are used together, the joint or seam between the several boards may be effectively concealed.
- 15 It is a further object of the invention to construct the wall board from a plurality of different materials with a reinforcing element interposed between the two materials employed.
- 20 It is a further object of the invention to provide a reinforcing element for wall board which reinforcing element is capable of taking fastenings, such as nails, screws, or the like.
- 25 With the above and other objects in view, reference is had to the accompanying drawings, in which—

Figure 1 is a plan view partly broken of a section of wall board formed in accordance with the present invention;

Fig. 2 is a detail transverse sectional view taken on the line 2—2 of Fig. 1;

Fig. 3 is an enlarged plan view partly broken away to show the construction of the wall board, and

Fig. 4 is a plan sectional view of a portion of a wall constructed from wall board formed in accordance with the present invention.

Referring again to the drawings and more particularly to Fig. 2, it will be noted that the wall board comprises a body portion 5, a facing 6, a reinforcing element 7, and reinforcing elements 8. The body portion 5 is formed from suitable cementitious material as is also the facing 6, and these materials are combined together to form a section of wall board. In uniting the body portion 5 and the facing 6, however, the reinforcing element 7 is interposed therebetween as shown in Fig. 2. This reinforcing

element 7 consists of a sheet of suitable fabric and is preferably of a relatively open weave to permit of the materials of the body and the facing passing therethrough in order to interlock on opposite sides thereof.

The reinforcing elements designated by the reference numeral 8 are wooden strips which are embedded in the body portion, and as shown in Fig. 2, the fabric reinforcing element 7 is wrapped around the edge-defining reinforcing strip 8 as designated by the reference numeral 10. A similar reinforcing strip of wood, 9, extends longitudinally of the section of wall board when completed, and such reinforcing strip 9 is wrapped or bound with a fabric reinforcing element designated by the reference numeral 11.

Each of the sections of wall board is formed with beveled side edges as designated by the reference numeral 12, and the reinforcing strips 8 extending along the side of the wall board are adapted to underlie a portion of the beveled edge 12 in order that nails inserted through the bevel will pass through the reinforcing strip and secure the wall board in position.

In Fig. 4 is shown the manner of erecting a wall with wall board constructed in accordance with the present invention, and in such figure the reference numeral 15 designates the studding and 16 designates a section of wall board. Fastenings 17, such as nails or the like, are driven through the beveled edge 12 of the sections of wall board and through the reinforcing elements 8 as shown. By providing the beveled edges as shown, a channel 18 is provided and such channel is filled with a suitable finishing plaster or the like, 19, to give a finish to the completed wall, and also to aid in maintaining the fastenings 17 in proper position.

From the foregoing it is apparent that the present invention provides a new and improved wall board. Thus all of the objects of this invention have been accomplished, and, further, it will be understood that numerous modifications of structure may readily be resorted to without in the least departing from the scope of the claim.

What is claimed is:

A wall board, comprising a cementitious body, wooden strips wholly enclosed in an open weave fabric and embedded in the body, a cementitious facing for the body, said facing having a portion of its ends thickened, and a sheet of an open weave fabric between the body and facing and wrapped entirely around the end wooden strip to form the enclosure therefor, the board having beveled edges and the outer portion of the end wooden strips underlying only a portion of the beveled edges. ¹⁰
